UNITED STATES PATENT OFFICE.

HOWARD MORTON HAY, OF CHICAGO, ILLINOIS.

SOUND-DEADENING AND ATTACHING DEVICE FOR WRITING-MACHINES.

1,069,693.

Specification of Letters Patent. Patented Aug. 12, 1913.

Application filed July 26, 1911. Serial No. 640,671.

To all whom it may concern:

Be it known that I, HOWARD M. HAY, a citizen of the United States, residing at Chicago, in the county of Cook and State of Illinois, have invented certain new and useful Improvements in Sound-Deadening and Attaching Devices for Writing-Machines, of which the following is a specification.

The purpose of this invention is to provide sound deadening attaching means for securing typewriting machines to desks or table tops in such manner that the machine may be readily released for any purpose, such as cleaning, or replaced, or the machine may be moved forwardly or rearwardly with respect to the desk or table without disturbing the connecting devices or lessening the effect of the sound deadening features. This permits the operator to adjust the machine to suit his convenience and when the attachments are applied to a combination desk in which the writing machine is made to disappear from view when not in use, the machine may be moved backward to permit the desk to close and will be securely held on its support when the latter is tilted or lowered.

In the accompanying drawing which illustrates my invention,—Figure 1 is a plan view of devices embodying my invention, showing the same connected to the frame of a typewriter machine, the latter being shown in horizontal section; Fig. 2 is a section taken on the line 2—2 of Fig. 1; Fig. 3 is a side view of one of the attaching devices; Fig. 4 is a plan view of the same; and, Fig. 5 is a perspective view of one of the hooked guide bars.

Referring to the drawing, A indicates a suitable supporting bed, such as a top of a desk or table, and B indicates a rectangular pad of sound deadening material, such as thick felt, which is laid upon the supporting bed. The frame C of the writing machine rests upon the pad B. As shown in Fig. 2, at the points where the rubber feet c of the writing machine frame rest upon the pad B the latter is provided with pockets b in which are inserted bags b' containing granular material b², such as sand, which serves as an additional sound deadening means and absorbs the vibrations of the machine, preventing their transmission to the supporting bed A. One bag of granular material is

arranged under each foot of the writing machine frame in the manner shown in Fig. 2.

The pad B, as shown in the drawing, has parallel sides and it rests loosely on the bed A so that when the machine is moved forward or rearward the pad will move with it.

Two strips D, of felt, are arranged at the sides of the pad B and upon the rear portions of these strips are arranged other shorter strips of felt d. These strips are secured together and to the bed A by screws 65 1 passing through sheet metal clips E having parts e pressed upwardly to form guideways or channels. Guide-bars F are arranged within these channels between the felt strips D and d. It will be seen that the 70 guide bars rest upon the strips D and that they are separated from the clips E by the felt strips d so that there is no connection between the guide-bars and the bed A except through the strips of sound deadening material. These guide-bars are held firmly by the clips, but are yet free to move forwardly and rearwardly within the guides when the machine is moved forward or rearward.

Each guide bar has at least one upwardly 80 turned hooked end, but they are preferably provided with two hooked ends f and f', as shown best in Fig. 5, the end f' projecting higher than the end f, the purpose of this being to have the guide bars interchangeable 85 for connection with latches held at different elevations on different forms of writing machines. The latches are engaged by the hooks at the forward ends of the guide-bars, the hooks at the rear ends serving as stops 90 to limit the forward movement of the machine. In the drawing, the frame of a Remington writing machine is shown and with this frame the latch G is supported in a lower position than on some other types 95 of machine and therefore the guide-bars F are arranged with the shorter hooked ends f at the front and with the longer hooked ends f' at the rear, although this would be reversed with some other types of machine.

The latches G, shown on each side of the machine, are similar in construction and interchangeable. Each latch comprises a base-piece 2 which is clamped to one of the lower side bars c' of the machine frame by a hook 105 3 passing over the side bar and provided with a clamping nut 3^a beneath the latch. To prevent the latch from twisting or turn-

ing it is provided with a lug 4, which fits against the inner face of the side bar *c'* and with a pair of lugs 5 which engage the outer face of the side bar, a sort of channel being formed by the lugs 4 and 5. The central portion of the base-piece is cut away, as indicated at 6, for the sake of lightness, and connecting with the opening 6 are notches or recesses 7 to receive the hooked ends of the 5 guide bars F. The parts 8 adjacent the opening 6 are flat and a latch bar 9 is supported by and is movable upon the flat parts 8. Upwardly projecting ribs 10 extend along the front and rear edges of the base 2 and these prevent longitudinal movement of the bar. The bar 9 is pressed by a spring 11 against a pair of shoulders, 12 and 12^a, adjacent the notches 7, which shoulders extend at right angles to the ribs 10, and a pair 15 of tongues 13, integral with the base, extend over the bar 9 parallel with the parts 8 and serve to guide the bar. The spring 11 presses against the central portion of the bar, said spring being held in position by 20 studs 14 and 15 on the base and bar respectively.

In applying the sound deadening and attaching devices, the latches G are secured to the frame of the machine as shown and the 30 hooked guide-bars F are arranged at the proper distance apart to engage the notches in the latches, and parallel with one another. The pad B is laid upon the support between the guide-bars and the writing machine is placed thereon so that its feet will rest upon the sand bags b'. When the machine is placed upon the pad the forward hooked ends of the guide-bars pass through the forward notches 7 in the latches, and 35 the latch bars 9 spring under the shoulders on said hooked ends. The machine is then secured to the table or support. It is evident that if the machine is pulled forward or moved rearward the guide-bars will move with the machine, and as the pad B is not secured to the support, it will also move forward and backward with the machine, which rests upon it. The sound deadening strips D are extended forward from the 40 clips E in order that the guide-bars F may rest upon the strips D when the machine is moved forward. If the machine is placed upon a disappearing support, the machine may be moved backward until the forward 45 hooked ends of the guide-bars strike the clips E, in order that the cover of the desk may close down without striking the machine, and when the support is tilted, the machine will be held securely thereon by the 50 connections described.

In order to remove the machine for the purpose of cleaning the same, or for any other purpose, the operator presses the forward knobs 9^a of the latch bars 9 inwardly, 55 which releases these bars from the hooks on

the guide-bars, as indicated in dotted lines in Fig. 4, and simultaneously lifts the forward end of the machine which carries the latches out of engagement with said hooked ends. The operation of removing the machine is accomplished with no more delay than would be required to lift the machine if the attachments were omitted and in replacing the machine it is only necessary to locate the proper notches in the latches over the forward hooks on the guide-bars and then lower the machine and it becomes automatically locked to its support. 70

It will be evident from an inspection of Fig. 4 that when one end of the latch bar 9 is moved inward, as indicated in dotted lines, the opposite end will fulcrum against the shoulder 12 and that the bar will fulcrum against the shoulder 12^a when its opposite end is pressed inwardly. By providing two notches 7 in each latch and arranging the latch bar as described, the latches used on opposite sides of the machine may be and are alike in construction and interchangeable. 75

What I claim is:—

1. The combination with a supporting bed for a writing machine, of a guide bar independent of the supporting means for the machine movable thereon, sound deadening material between said bar and the bed, a guide for said bar, and means for securing a writing machine to said bar. 80

2. The combination with a supporting bed for a writing machine, of a guide bar independent of the supporting means for the machine movable thereon, and having an upwardly projecting hook, sound deadening material between said bar and bed, a guide for said bar and a latch secured to the 100 machine frame and adapted to engage said hook. 105

3. The combination with a supporting bed for a writing machine of two layers of sound-deadening material thereon, at each side of the machine, guide bars independent of the supporting means for the machine arranged between said layers, guides for said bars upon said layers, and means for connecting said guide bars with the 110 machine frame. 115

4. The combination with a supporting bed for a writing machine of two layers of sound-deadening material thereon, at each side of the machine, guide bars independent of the supporting means for the machine arranged between said layers, guides for said bars upon said layers, and means for connecting said guide bars with the machine frame comprising hooks on the guide 120 bars, latches for engaging the hooks, and means for securing the latches to a machine frame. 125

5. The combination with a supporting bed for a writing machine, of sound-dead- 130

5 ening material thereon, a guide bar independent of the supporting means for the machine movable on said material, and means for securing a writing machine to said bar.

10 6. The combination with a supporting bed for a writing machine, of sound-deadening material thereon, parallel guide-bars independent of the supporting means for the machine movable on said material, and means for securing a writing machine to said bars.

15 7. The combination with a supporting bed for a writing machine, of sound-deadening material thereon, parallel guide-bars independent of the supporting means for the machine movable on said material, said guide-bars having upwardly projecting hooks, latches adapted to engage said hooks, and means for securing said latches to a writing machine frame.

20 8. Means for securing a writing machine to a supporting bed comprising devices provided with hooks, means for securing said devices to the bed, and latches for engaging said hooks, each of said latches comprising a base provided with a pair of notches, a latch bar in sliding engagement with said base and extending across both notches, and a spring bearing against the central portion of said bar.

25 9. Means for securing a writing machine to a supporting bed comprising devices pro-

30 vided with hooks, means for securing said devices to the bed, and latches for engaging said hooks, each of said latches comprising a base provided with a pair of notches, and shoulders adjacent said notches, a latch bar in sliding engagement with said base and having its ends adapted to bear against said shoulders, and a spring pressing said bar toward the shoulders.

35 10. Means for attaching a writing machine to a supporting bed comprising a pair of guide bars independent of the supporting means for the machine each bar having two upwardly projecting hooked portions, guiding means for said bars, latches adapted to engage said hooked portions and means for securing said latches to the machine.

40 11. The combination with a supporting bed for a writing machine, of a pad, of sound-deadening material movable on said bed and arranged to support the machine, strips of sound-deadening material at the sides of said pad, guide-bars independent of the supporting means for the machine slidably mounted on said strips and means for connecting said bars with the machine frame.

45 In testimony whereof I affix my signature, in presence of two witnesses.
